UNITED STATES PATENT OFFICE.

SHERMAN M. PIERCE, OF KANSAS CITY, MISSOURI, ASSIGNOR OF ONE-HALF
TO CHAUNCEY S. COLTON, OF SAME PLACE.

ELECTRIC ROTARY AND REVOLUBLE AIR-CIRCULATING FAN.

SPECIFICATION forming part of Letters Patent No. 534,481, dated February 19, 1895.

Application filed October 20, 1894. Serial No. 526,503. (No model.)

To all whom it may concern:

Be it known that I, SHERMAN M. PIERCE, a citizen of the United States, residing at Kansas City, in the county of Jackson and State of Missouri, have invented certain new and useful Improvements in Electric Rotatory and Revoluble Air-Circulating Fans, of which the following is a specification.

The electric rotatory and revoluble air circulating fan to which the invention that is herein described pertains is of that class in which the fan wheel is rotatory around an axis, and is, together with the motor which rotates the fan wheel, revoluble around another axis, which axis of revolution is at a right angle or approximately at a right angle to said axis of rotation, and which fan wheel by its rotatory motion forces a current of air from its immediate vicinity, and by its revoluble motion with the motor, in a circular orbital path, forces said current of air radially from its circular orbit, in every direction substantially in a line with its axis of rotation, or in other words, in every direction substantially in its plane of revolution; and the leading object of my invention is to provide improved, novel, simple and effective means, involving a new mode of operation, for simultaneously revolving the motor and fan wheel, by utilization of the current of air passing to the fan wheel; and to this end and object my invention consists in its main feature in a combination, with a fan wheel and motor of the class or type referred to, of a vane or vanes fixed in position or positions as the case may be, relatively to the motor, and in the trajectory or path of the air current, as said current is passing to the fan wheel, whereby said vane or vanes, while not interfering with the rotation of the fan wheel, will be carried around with the fan wheel in its orbital movement, and always within the trajectory of the air current passing either to or from the fan wheel, as the case may be, and which air current is the source of propulsive energy continually acting on the vane or vanes, while the fan wheel is being rotated to force the motor and fan wheel simultaneously around in their respective circular orbits on the axis of revolution.

The different improvements and different combinations which have been evolved in

carrying out the main objects of my invention, the separate and collective operations of the parts comprised in the invention, the new mode of operation and useful results arising therefrom are hereinafter described, and the new combinations are made the subject matter of claims hereto appended.

In the accompanying drawings all my improvements are shown as constructed and embodied in a preferred way, and in the best way now known to me. Obviously however, while still within the purview of my invention, some or all of the parts may differ in their construction, in their organization, their disposition for co-action, and be embodied in other forms and ways from what I have shown in said drawings, in which—

Figure 1 is a sectional elevation in the line 1—1 in Fig. 2, showing the electric motor in section, and one of the fan wheels and a vane in elevation; and Fig. 2, a top plan.

The electric motor A comprises field magnets B, yoke or keeper C, fiber washers D, core studs E, pole pieces F, armature G, armature shaft g, bearing bar g' for the armature, through bolts g² for supports for the bearing bars g', for the insulating sleeves g³ and for the brushes g⁴.

The electric motor shown is of ordinary construction, and need not be any more fully herein described.

A preferred way of revolubly suspending the motor and thereby the fan wheels is shown at Fig. 1, in which a spindle H rising from a wooden or other suitable base I passes through the yoke C, and has a conical and suitably hardened upper end which forms a pivotal point for an inverted step j in a bearing bridge or plate J, which extends from one of the field magnets to the other at their upper ends. A preferred way of making the electrical connections is also shown at Fig. 1, in which the wires k, k', connected in any source of electrical supply, (not shown,) are connected, the one, k, with a ring commutator l, and the other, k', with a ring commutator l', both of which ring commutators are supported on the base I, concentric with each other and with the spindle H. A spring plate or brush m, preferably of copper, fixed at one end thereof in a recess c' below one of the field magnets and

in the lower surface of the yoke C, and insulated therefrom by a fiber block n, rests at its other end in constant contact with the ring l, as the motor revolves on the vertical spindle 5 H, and a similar spring plate or brush m' fixed at one end thereof in a recess c² below the other field magnet and in the lower surface of the yoke C, and insulated therefrom by a fiber block n', rests at its other end in constant contact with the ring l'. The brushes m, m' are connected with the field magnets as shown.

The fan wheels P, each formed of a series of radial fans p, are fixed one to each of the outer ends of the armature shaft, g, and are rotated by and with the armature shaft. Each fan p transversely thereof is oblique to its plane of rotation with the armature shaft and armature, and its obliquity is in such direction that when the fan wheels are rotated by the motor driven by the electric current, in the direction shown by the arrows x at both figures of the drawings, each fan wheel will force a current of air outwardly from the motor located between said fan wheels, or in other words, the fan wheels will each force a current of air outwardly and in an opposite direction to the current of air forced outwardly by the other fan wheel.

Two propeller vanes R are shown in the drawings, for giving the revoluble motion in horizontal planes to the motor and fan wheels, as hereinafter described. A vane R is located a short distance from each fan wheel, and, as shown at Fig. 2, on that side of each fan wheel which confronts the other fan wheel, so that the propeller vane for each fan wheel will be within the field of air force, or path of the current of air flowing toward its adjacent fan wheel, and which current or air force arises from the induced flow of air to supply the partial vacuum produced by the action of the fan wheel in forcing a current of air outwardly from its other side.

In order that both vanes R may operate to revolve the motor and fan wheel in the same direction, they are arranged to protrude in opposite directions from the motor, as shown at Fig. 2. The inner end of each vane R is fixed to the motor by bolting it to the adjacent end of a bolt g² or otherwise as may be preferred. The force action of the current of air, in the direction, merely indicated by the dot line arrows at Fig. 2, as it approaches the fan wheels, will act on the vanes R and thereby tend to force them around, and thus revolve the motor and impart to the fan wheels a movement of translation, or revoluble motion in a circular orbit. This orbital or revoluble motion of the fan wheels will cause them to force the current of air produced by their rotary motions in every radial direction from their orbital paths. The two vanes R will also impart a more rapid rate of revolution to the fan wheels than will one vane. It will be understood, however, that the rate of speed of the motor and fan wheels

in revolving, should not be too rapid, while the rate of speed of the fan wheels in rotating should be very rapid.

As it is shown in the drawings, the machine is designed to be held on or by a support, in the central part of the room, and to distribute air in motion in every direction horizontally and radially from the circular orbital path of the fan wheels. It will be evident, however, that they may be used either singly or in any desired number, in various locations in a chamber, room, hall, or other place where desired.

There being two of the fan wheels forcing currents of air in opposite directions, the current of air in any given direction from the machine will be much more nearly continuous, and hence much more effective and satisfactory than with only one fan wheel. With a fan wheel on each end of the armature shaft, said shaft will be in equilibrium in its bearings, and will not be drawn or forced endwise of itself and against its bearings, as will be the case if only one fan wheel is used, or in other words, with the two fan wheels in a pair on the same shaft, and adapted to receive the air between them, the pressure of the air upon one wheel endwise of the shaft will be counterbalanced by the equal and opposite pressure of the air upon the other wheel, and thus the endwise strains upon the shaft will be counterbalanced and the bearings of the shaft relieved of strains. It will be evident, however, that one fan wheel with its co-acting vane R, will impart the revoluble motion to the motor and fan wheel, and hence I consider my invention, in this respect, as broadly including the combination of the propeller vanes with either one or two fan wheels. It will also be evident that electrical motors of different types may be used with my main improvements, and that other than electrical motors may be used therewith. Hence I consider my invention, in this respect, as broadly including the combination of the propeller vanes with the fan wheel or fan wheels and any motor to which they can be applied within the current of air flowing toward the fan or fans for the same object and purpose for which they are used in my invention. It will also be evident that the machine may be pivotally suspended from a ceiling or other horizontal, inclined or vertical support. Hence I consider my invention as broadly including the propeller vane or vanes located within the current of air flowing to the fan wheel or wheels, and in combination with the fan wheel or fan wheels and motor when suspended in any manner in which they have the same object and purpose for which they are used in my invention.

What I claim as new, and desire to secure by Letters Patent, is—

1. In a rotatory and revoluble air circulating fan, in combination, substantially as hereinbefore described, a motor, a pivot support on which the motor revolves, a fan wheel ro-

tatable with the motor armature, or rotatable part or shaft of the motor and a propeller vane fixed to revolve with the motor and fan wheel, and located within the current of air flowing toward or leading to the fan wheel, whereby said current of air is made to revolve the propeller vane, the motor and fan wheel.

5 2. In a rotatory and revoluble air circulating fan, in combination, substantially as hereinbefore described, an electric motor, a pivotal support on which the motor revolves, fan wheels, fixed one to each end of the motor armature shaft to rotate therewith, and propeller vanes fixed to revolve with the motor and fan wheels and located, one within the current of air flowing toward or leading to each fan wheel, whereby the currents of air induced by the fan wheels are made to revolve the propeller vanes, the motor and fan

10 15 20 25 30 35 40 45 50 wheels.

3. In a rotatory and revoluble air circulating fan, in combination substantially as hereinbefore described, a base, a vertical spindle supported on said base, an electric motor revolubly mounted on said spindle, fan wheels fixed one to each end of the armature shaft to rotate therewith, and propeller vanes fixed to revolve with the motor and fan wheels, and located, one within the current of air

flowing toward or leading to each fan wheel, whereby the currents of air induced by the fan wheels are made to revolve the propeller vanes, the motor and fan wheels.

4. The combination with a fan wheel, a shaft by which the fan wheel is carried around in a circular orbit, and means for rotating said shaft and with it the fan wheel, of a propeller vane fixed to revolve with the fan wheel, but not to rotate therewith, and located in the current of air passing to the fan wheel, whereby said current of air is made to revolve the propeller vane and the fan wheel, substantially as described.

5. The combination with an electric motor, and its rotatory part or shaft, of a fan wheel on each end of said rotatory shaft, each fan wheel adapted to force a current of air in an opposite direction to its fellow fan wheel, whereby the endwise strains upon the shaft are counterbalanced and the bearings of the shaft relieved of strain, substantially as described.

In testimony whereof I affix my signature in presence of two witnesses.

SHERMAN M. PIERCE.
